UNITED STATES PATENT OFFICE.

WILBUR G. DAVIS, OF CONCORD, MASSACHUSETTS.

BUCKLE FOR HARNESS.

SPECIFICATION forming part of Letters Patent No. 623,704, dated April 25, 1899.

Application filed April 14, 1898. Serial No. 677,600. (No model.)

To all whom it may concern:

Be it known that I, WILBUR G. DAVIS, of Concord, county of Middlesex, State of Massachusetts, have invented an Improvement in 5 Single Harness, of which the following description, in connection with the accompanying drawings, is a specification, like letters and numerals on the drawings representing like parts.

10 This invention has for its object the production of a very strong, simple, and convenient buckle particularly adapted for use with harness.

15 Figure 1 is a perspective view of the front ends of a pair of shafts with a harness applied thereto having buckles embodying my invention. Fig. 2 is an enlarged plan view of the novel form of buckle which I have devised, shown in Fig. 1 as employed for detachably 20 connecting the breast-collar and draft members; and Fig. 3 is a longitudinal sectional view of the breast-collar and draft member with the buckle in side elevation.

25 In my present invention I have departed entirely from the usual and well-known form of tongue-buckle, as will fully appear hereinafter.

The harness, as shown in Fig. 1 and with 30 which I have chosen to illustrate my novel buckle, comprises a saddle having attached shaft-tugs for the reception of the shafts a and a breast-collar detachably connected by my novel buckles with the draft members or 35 traces. The flexible ends or straps a^5 of the draft members, shown as extended into hollow shaft-tips a^3 , have each a hole 3 therein, Figs. 1, 2, and 3, to receive the holding or retaining prong of the buckle on the breast-collar B. This breast-collar is adapted to be 40 detachably connected with the draft members, and for this purpose my novel form of buckle is particularly adapted, the buckle comprising two separable members b b' , hinged together at b^2 , with a holding-prong b^3 45 on one member adapted to be locked to the other member. Herein I have shown the member b as a flat plate of steel provided with an upright rigid holding-prong b^3 , provided, as shown in Fig. 3, with two annular 50 grooves or recesses 4 and 5 and having a rounded laterally-extended head 6. The member b' is shown as made of a single piece

of stiff spring metal bent or shaped into loop form, the straight bar b^2 at the wide end of the loop being preferably rounded between its 55 ends, as at b^4 , to form a hinge-joint between the two members b and b' , a U-shaped clip b^5 , attached to the former, embracing the rounded part of the bar b^2 . The free ends of the loop-like member b' are brought together 60 at b^6 , each end having its inner face recessed, as at b^7 , Fig. 2, so that the two registering recesses form a spring clip or catch to receive and tightly embrace the holding-prong, the head 6 of the latter preventing accidental 65 disengagement of the catch. I have shown the base plate or member b as embedded in the leather forming the breast-collar B, with the holding-prong b^3 extended through and beyond the outer face thereof, and the sides 70 of the loop-like member b' straddle the latter, as clearly shown in Fig. 2.

The strap end a^5 of the draft member is passed through a box-loop B' at the end of the breast-collar, and the prong b^3 is passed 75 through the hole 3 in the strap a^5 , the free end of the latter passing through the loop or open member b' , and the latter is then turned down and locked in place upon the prong, as in Fig. 3. 80

When it is desired to detach the breast-collar from the draft member, the operator will preferably insert his fingers between the collar and the strap a^5 and will pull the latter outward to thereby raise the member b' of the 85 buckle from engagement with the prong, (see dotted-line position, Fig. 3,) the increased leverage thus gained materially assisting in the disengagement, as the spring-catch is purposely made stiff and strong. 90

The construction of the buckle is such that it can be manipulated with one hand, and after it is unlocked the strap is not detached from the holding-prong until it is positively removed therefrom. 95

From an inspection of Figs. 2 and 3 it will be obvious that the buckle is very strong and adapted to successfully resist a great strain without damage.

Referring to Fig. 2, one of the free ends, b^6 , 100 of the loop member of the buckle has a lateral counterbored hole 33 (see dotted lines) to receive loosely a headed pin 35, which is tapped into the opposite end b^6 of the loop, the coun-

terbore permitting free movement of the head of the pin, the latter serving to positively limit the extent of lateral separation of the ends of the loop and insure bodily movement of the ends in unison.

Having fully described my invention, what I claim, and desire to secure by Letters Patent, is—

1. A buckle comprising hinged members, 10 an upright holding-prong on one of said members, a spring-lock having laterally-separable portions on the other member, to engage and tightly embrace the prong and retain the members from separation, and a stop to limit the 15 separation of the spring portions of the lock, substantially as described.
2. A buckle comprising an attaching member having an upright, headed holding-prong provided with two annular recesses, a coöperating loop-like member hinged to the attaching member and having a locking device 20 to directly engage the upper recess of the holding-prong below its head and prevent separation of the members, the lower recess 25 being adapted to engage the free end of the strap, substantially as described.
3. A buckle comprising an attaching member having an upright, headed holding-prong, and a coöperating loop-like member pivotally connected at the enlarged back of the 30 loop with the attaching member, and having laterally-separable spring ends recessed near

their extremities to receive and directly engage the holding-prong and thereby lock the two members from separation, substantially 35 as described.

4. A buckle comprising an attaching member having an upright holding-prong, a coöperating loop-like member having a straight portion forming its closed back and hinged 40 to the attaching member, the adjacent free, and laterally-separable spring ends of the loops being recessed to receive and tightly embrace the holding-prong, to thereby form a lock for and prevent separation of the two 45 members.

5. A buckle comprising an attaching member having an upright holding-prong, a coöperating loop-like member having its free spring ends brought together and recessed on 50 their inner sides to receive and tightly embrace the holding-prong, the loop being broadened beyond the spring ends to receive the free end of the strap, and pivotally connected at its broadest portion with the attaching 55 member, substantially as described.

In testimony whereof I have signed my name to this specification in the presence of two subscribing witnesses.

WILBUR G. DAVIS.
